Attn:

UNITED STATES PATENT OFFICE.

RUSSELL H. LEWIS, OF PROVIDENCE, RHODE ISLAND, ASSIGNOR TO ROBERT S. CUTTING, OF SAME PLACE.

BUTTON.

SPECIFICATION forming part of Letters Patent No. 365,693, dated June 28, 1887.

Application filed January 25, 1886. Serial No. 189,711. (No model.)

To all whom it may concern:

Be it known that I, RUSSELL H. LEWIS, of the city and county of Providence, and State of Rhode Island, have invented certain new and useful Improvements in Buttons, of which the following is a full, clear, and exact description, reference being had to the accompanying drawings, forming part of this specification.

10 My invention relates to the class of non-separable buttons which have the shoe actuated by a spring and hinged upon the end of the shank, whereby the shoe can be made to assume three different and definite positions—viz, a 15 position at right angles to the shank, a position parallel to the front of the shank, and a position parallel to the rear of the shank.

The object of my invention is to provide a button of this class which is ordinarily used 20 to hitch parts of garments together, which is simply constructed of a few durable parts, and whose shoe will securely maintain the several positions it may be thrown into in operating the button.

25 To the above purposes my invention consists in the new and peculiar constructions and arrangements of its parts, as hereinafter fully described and claimed.

In the accompanying drawings, Figure 1 30 represents a front elevation of my button with the shoe at right angles to the shank. Fig. 2 represents a side elevation of Fig. 1. Fig. 3 represents a side elevation of my button with the shoe thrown down parallel to the shank 35 for inserting it in or withdrawing it from the button-hole. Fig. 4 represents an enlarged vertical central sectional view of my button, taken in a plane cutting the same from front to rear. Fig. 5 represents a top plan view of 40 Fig. 4 with the cap-plate 13 removed. Fig. 6 represents same view as Fig. 4, showing a modified form of my shoe with a part of the shank.

In the said drawings like figures designate 45 like parts throughout.

Referring to the drawings, the head 7 of the button is a concavo-convex disk, constructed, as usual, with a covering, and from whose concave face arises the shank 8, which is broad 50 and flat, and near its end has a perforation or slot, 9. The shoe 10 of the button I construct

in the primary form of three parts, consisting of the spring-plate 11, having the tongue, the tie-piece 12, and the cap-plate 13. In the modified form of Fig. 6 I employ but two pieces— 55 the spring-plate 11 and cap-plate 13—the tie-piece 12 being dispensed with by virtue of the peculiar construction of the tongue of the spring-plate. The spring-plate 11 is a flat disk, which is slit to form the tongue 14, which arises 60 from near the center of said disk, and the displacement of which tongue forms the slot 15 in the disk. This tongue 14 is bent downwardly, forwardly, then upwardly, and again forwardly. This loop in the tongue is made 65 for the same to take into the slot 9 and about the pintle-bar 16, whose inner face affords a bearing for said tongue when the shoe has the position shown in Figs. 4 and 6. The free end of said tongue is bent forwardly and in a plane 70 above the upper face of the spring plate 11, in order to allow the insertion of the tie-piece 12, which lies flat upon the upper face of spring-plate 11 and crosses the slot 15 about midway, and serves to hold securely the free end of said 75 tongue, thereby permitting the same to spring-actuate the shoe. The cap-plate 13 is sprung over the upper face of the spring-plate and about the edge of the same.

In the modified form of Fig. 6 the tie-piece 80 is not used, and instead the cap-plate 13 is employed to hold securely the free end of tongue 14, which is here curved upwardly, instead of being flat, to give the tongue more resiliency. In this modified construction there are, in fact, 85 but two parts to the shoe—the spring-plate 11, with its tongue 14, and the cap-plate 13. It is obvious that either the tongue 14 may be resiliency and the tie-piece unyielding or the tongue may be unyielding and the tie-piece 90 resiliency, in order to give the desired spring action to the shoe. I have preferably shown the former method of making the shoe spring-actuated. When the shoe is placed at right angles to the shank, the resiliency of the tongue 95 14 causes the spring-plate 11 to press hard upon the free end of shank 8 and the loop of the tongue to press hard upon its bearing on the inner face of pintle-bar 16. This spring force maintains securely the shoe in position. 100 When either the front or rear of the shoe 10 is depressed, the bearing of the tongue upon

the pintle-bar is shifted to either rear or front face of said bar, according as the front or rear of shoe 10 is depressed.

My button can be constructed without solder and still be durable and have its positive action.

There may be various modifications made in the essential parts of my button without departing from the spirit of my invention, as herein described and claimed. For instance, the tongue 14 may be modified by having near its end two lateral fangs to hold said tongue, instead of the tie-pieces 12.

Having thus described my invention, I claim as new and desire to secure by Letters Patent—

1. The combination of a button-head and a shank therefor, a complete movable shoe consisting of a spring-plate adapted to work and have its fulcrum on the end of said shank, and provided with an integral spring-tongue suitably bent and hinging with said shank, and a cap-plate secured over said spring-plate, said spring-tongue being held from displacement by means substantially as described.

2. In combination, a button-head and a shank therefor, and a complete movable shoe formed of the following elements—namely, a spring-plate, a spring-tongue displaced or cut from said spring-plate, said tongue suitably bent and hinging with said shank, a tie-piece interposed between said spring-plate and near the free end of said tongue, and a cap-plate sprung over said spring-plate.

3. In combination, the button-head pro-

vided with a shank having a transverse slot near the free end, and the complete movable shoe 35 composed of the following elements—namely, the circular spring-plate, the integral spring-tongue cut from the spring-plate at two points on the circumference in lines to near the center of said plate, said tongue formed with a bend 40 between the fixed end and the free end thereof, said bend hinging with said slot, a flat tie-piece interposed near the free end of said tongue between said tongue and the upper face of the spring-plate, and the circular cap-plate 45 secured about the rim of said spring-plate over the upper face thereof, substantially as described.

4. The combination, with the head 7, provided with the shank 8, having slot 9, of the 50 movable shoe 10, consisting of the spring-plate 11, the bent spring-tongue 14, hinging with said shank 8, the tie-piece 12, holding the free end of said tongue 14, and the cap-plate 13, substantially as described.

5. The combination, with a button-head provided with a shank, of the movable shoe composed of the spring-plate 11, the bent spring-tongue 14, integral with said plate, the tie-piece 12, and the cap-plate 13, substantially as de- 60 scribed.

RUSSELL H. LEWIS.
